SPLITTING MACHINE

Thomas B. Clarke and Hubert Boothroyd, Leicester, England, assignors to United Shoe Machinery Corporation, Paterson, N. J., a corporation of New Jersey

Application June 23, 1936, Serial No. 86,827
In Great Britain July 16, 1935

8 Claims. (Cl. 69—13)

This invention relates to the manufacture of shoes and is illustrated as embodied in a splitting machine.

It is common practice to split heel-breast covering flaps, for example, from the grain sides of soles of shoes by the use of a machine which comprises a stationary splitting knife and a pair of rolls for feeding the sole against and past the cutting edge of the knife, one of the rolls being initially adjusted by the operator with relation to the knife in accordance with the desired thickness of the flap and the other roll being pressed yieldingly against the sole to cause the same to be gripped between the rolls and fed against the knife as the rolls rotate.

It has been found that when soles of soft leather are gripped between the rolls the same are compressed to a considerable extent. When this occurs the flap, due to its expansion after it leaves the roll, is thicker than the setting of the upper roll calls for, the thickness of the split flap varying in accordance with the density of the leather.

It is an object of the present invention to split from work pieces of substantially uniform thickness and varying densities flaps which are of substantially uniform thickness.

With the above object in view and in accordance with a feature of this invention, there is disclosed a machine comprising a fixed knife provided with an elongated cutting edge, a feed member which is initially adjustable with relation to the cutting edge of the knife to provide a gap of predetermined width in accordance with the desired thickness of a piece of material to be trimmed from a work-piece, a yieldable feed member movable with relation to the knife in accordance with the density of the work-piece fed by the members past the knife, and mechanism for causing movement of the yieldable feed member in one direction to effect a proportionately less movement of the other feed member in an opposite direction.

The invention will be better understood and appreciated from the following detailed description thereof read in connection with the accompanying drawing, in which

Fig. 1 is a front elevation, partly in section, of a portion of a splitting machine embodying our invention;

Fig. 2 is a vertical section of the machine taken along line II—II of Fig. 1;

Fig. 3 is a detail sectional view of the machine taken along line III—III of Fig. 1; and

Fig. 4 shows a pair of rolls which are used in the

machine equipped to split heel-breast covering flaps from soles of shoes.

The illustrated machine comprises a main frame 10 to which a splitting knife 12 having a cutting edge 14 is adjustably secured through the provision of a slot-and-screw connection 16 (Fig. 2). The main frame 10 is provided with opposed vertical guideways 18 (Fig. 2) in which bearings 20, 22 (Fig. 1) of upper and lower rolls 24, 26, respectively, are slidably mounted. As above stated, it is desirable that the width of a gap 28 (Fig. 2) formed between the cutting edge 14 of the knife 12 and the upper or gage roll 24 shall be varied in accordance with the density of the work piece being split. The upper roll 24 is therefore operatively connected to the lower roll 26 so that vertical movement of the lower roll 26 in one direction will cause a proportionate vertical movement of the upper roll 24 in an opposite direction.

A bracket 30 is secured to the main frame 10 above the feed roll 24 of the machine. The bracket 30 is closed at its ends by cover plates 32 and at its under side by a cover plate 34. Slidably mounted in the bracket 30 above a horizontal upper roll adjusting bar 36 is a wedge bar 38 which is movable widthwise of the machine in a direction parallel to and lengthwise of the rolls 24, 26. The wedge bar 38 is provided with upper and lower faces 40, 42 (Fig. 1) inclined to each other, the angle between the faces being four or more degrees and the distance between the relatively inclined faces at each end of the bar increasing toward the right. Between the lower inclined faces 42 of the wedge bar 38 and the upper horizontal face of the adjusting bar 36 are two vertically movable blocks 44 which are prevented from movement forwardly and rearwardly of the machine by the bracket 30 and laterally of the machine by the cover plates 32, 34. The blocks 44 have horizontal lower faces resting on the upper face of the adjusting bar 36. The upper faces 46 of the blocks 44 are arranged in parallel relation to the inclined faces 42 of the wedge bar 38 and between these faces are anti-friction rolls 48 held in place by cages 50. Above the inclined faces 40 of the wedge bar are blocks 52 having lower faces 54 arranged in parallel relation to the upper inclined faces 40 of the wedge bar 38 and between these faces are anti-friction rolls 56 held in place by cages 58. The blocks 52 are provided with recesses 60 shaped and arranged to receive the lower ends of vertical screws 62 in threaded relation with the bracket 30 and carrying lock nuts 64. The screws 62 prevent the blocks 52 from being moved laterally of the machine and

the front and rear faces of the bracket 30 prevent the blocks 52 from being moved forwardly or rearwardly of the machine. The screws 62 provide means whereby when assembling the machine the upper roll 24, which is urged upwardly by springs 63, may be positioned heightwise relatively to the cutting edge 14 of the knife 12.

The lower bearings 22 are urged upwardly by springs 63 respectively, the upper ends of which engage the bearings and the lower ends of which engage studs 65 which are in threaded engagement with the main frame 10. Upward movement of the rolls under the action of the springs 63 is limited by the engagement of nuts 67 carried by depending extensions 69 of the bearings with the studs 65.

The wedge bar 38 has pivotally mounted on it at about the center of the machine a horizontal stud 68 (Fig. 2) which is secured to a pendulous arm 70. Pivotally mounted upon forwardly projecting pins 72 secured to the bracket 30 at equal distances from the central plane II-II of the machine are two depending control arms 74. The control arms 74 are arranged at opposite sides 25 of the pendulous arm 70 and carry blocks 76 which may be adjusted upwardly and downwardly on the control arms 74. The blocks 76 are provided with rounded projections which engage opposite sides, respectively, of the pendulous arm 30 70 at different portions heightwise of the arm. Secured to the lower ends of the control arms 74 by screws 78 are cam pieces 80 having cam faces 82, respectively, arranged to be engaged by rounded projections 84 of plates 86 secured to the vertically movable bearings 22 in which the lower roll 26 is mounted.

The bar 36 is adjusted laterally of the machine by a horizontal screw 88 which is rotatably mounted in an upwardly extending portion 93 of the left-hand bearing 20 of the upper roll 24 but is prevented from endwise movement therein. The left-hand end of the screw 88 has secured to it a wheel 90, the screw 88 being in threaded relation with a rectangular nut 92 (Figs. 1 and 3) engaging within a recess formed in an upwardly extending portion 93 (Fig. 3) of the left-hand bearing 20. The left-hand end of the adjusting bar 36 is forked and arms 94 of the fork pass behind and in front of upwardly extending portions 93 of the left-hand bearing 20 of the upper roll 24, the arms 94 having formed in their inner faces vertical grooves 96 shaped and arranged to receive projections 98 extending forwardly and rearwardly from the nut 92. When the screw 88 is rotated the nut 92 is moved laterally of the machine in the recess in the upwardly extending portion 93 of the left-hand bearing 20 of the upper roll 24 and is prevented from rotating by its engagement with the upper and lower walls of the recess and, by engagement of the projections 98 with the grooves 96 in arms 94 of the adjusting bar 36, moves the bar upwardly or downwardly with relation to the cutting edge 14 of the knife 12. By supporting the means for adjusting the bar 36 laterally of the machine on the bearings 20 of the upper roll 24 the bar is able to move bodily upwardly as will hereinafter appear.

When a work piece enters between the feed rolls 24, 26 the lower roll 26 is moved downwardly and the springs 63 which urge the lower roll upwardly compress the work piece between the rolls and thus exert an upward pressure against the upper roll 24. As the lower roll 26 descends, the rounded projections 84 on plates 86 secured to the

bearings 22 move downwardly away from the cam faces 82 on the cam pieces 80 carried by the control arms 74 and allow the control arms to swing away from each other on their pins 72. Owing to the angle at which the relatively inclined faces 40, 42 at each end of the wedge bar 38 are relatively arranged, the wedge bar, through the mechanism above described, is moved to the right by the pressure of the inclined faces 40, 42 exerted by the pressure of the work against the upper roll 24. Such movement of the wedge bar 38 allows the upper roll 24 and the adjusting bar 36 to move upwardly. As the wedge bar 38 moves to the right the pendulous arm 70, which is pivotally supported by the wedge bar, by its engagement with the rounded projections of the blocks 76 on the control arms 74, causes the latter arms to swing outwardly and the cam faces 82 on the cam pieces 80 of the control arms to move into engagement with the rounded projections 84. The engagement of the cam faces 82 with the rounded projections 84 limits the movement to the right of the wedge bar 38 and therefore determines the amount of upward movement of the upper roll 24. The amount the upper roll 24 is allowed to move upwardly when the lower roll 26 moves a given distance downwardly is controlled by the shape of the cam faces 82 of the cam pieces 80. The cam faces 82 may be so shaped that the amount of upward movement of the upper roll 24 is in a particular proportion to the amount of downward movement of the lower roll 26. This proportion may be varied by adjusting the blocks 76 on the control arms 74 which engage the pendulous arm 70 so that for a given downward movement of the lower roll 26 the wedge bar 38 receives an increased or decreased movement to the right and therefore varies the amount which the upper roll 24 rises.

In order to limit the extent of upward movement of the upper roll 24 a stop screw 100 is adjustably mounted on the right-hand cover plate 32 and is arranged to be engaged by the right-hand end of the wedge bar 38. The screw 100 is preferably adjusted so that the limit of upward movement of the upper roll 24, permitted by downward movement of the lower roll 26, will be about 7 or 8 thousandths of an inch but may be varied if desirable. The shape of the cam faces 82 and the adjustment of the block 76 on the control arm 74 determines the thickness of the work piece necessary to cause the wedge bar 38 to be moved into engagement with the stop screw 100.

The movement of the various parts of the mechanism when a work piece enters between the rolls 24, 26 is comparatively rapid, the raising of the upper roll 24 taking place before the leading end of the work piece has reached the cutting edge 14 of the knife 12. Upward or downward movement of the lower roll 26 as the work piece passes between the rolls, due to the varying density of the material, causes the position of the upper roll 24 in relation to the cutting edge 14 to vary.

The illustrated machine comprises a pair of arms 102 which engage opposite edges of the work piece to guide the same centrally between the rolls 24, 26. The arms 102 are pivoted upon pins 72 on which the control arms 74 are pivoted, the guiding arms 102 extending downwardly in front of and close to the rolls 24, 26 so that their lower inner ends engage the edges of the work piece. The guiding arms 102 are drawn toward each other by a spring 104 opposite ends of which are secured to the respective arms, the hubs 75

of the arms being in geared relation so that the arms are moved equal distances toward and away from the central plane II—II of the machine.

The hand wheel 99 by which the adjusting bar 36 is moved laterally of the machine is provided with spaced notches 106 which are engaged by a leaf spring 108, secured to the upwardly extending portion of the left-hand bearing 20 of the upper roll 24. The notches 106 are so positioned that rotation of the hand wheel from one notch to the succeeding notch causes the upper roll 24 to move upwardly and downwardly a quarter of an iron, one iron being equal to $\frac{1}{4}$ of an inch. This arrangement enables the operator quickly to adjust the upper roll 24 a desired amount if it is found by measurement of the work piece which has been split, that adjustment of the roll is necessary. The above arrangement may be used in addition to an indicator 110 which carries a pin 112 (Fig. 2) constructed and arranged to engage within a vertical slot 114 of the adjusting bar 36. The indicator 110 swings over a graduated plate 116 and shows in irons the distance of the upper roll 24 from the cutting edge 14 of the knife 12.

In splitting heel-breast covering flaps 118 (Fig. 4) it is desirable that the split sole be withdrawn from the machine in a direction opposite to the direction of feed and without any interference by the machine parts.

To equip the machine for splitting flaps a pair of rolls 120, 122 and roll-operating mechanism (not shown) such as disclosed in United States Letters Patent No. 1,638,929, granted August 16, 1927 on an application filed in the names of Joseph Gouldbourn and Wilfrid T. Minett, are provided. The upper roll 120 has a flattened surface 124, the lower roll being cylindrical throughout its periphery. At opposite ends of the rolls 120, 122 are cams 126, 128, respectively, so arranged that when the cams are in engagement the face 124 is in opposed relation with the lower roll 122 which is depressed against springs 63. The operating mechanism for the machine is so constructed and arranged that the machine stops when the rolls 120, 122 are arranged in the position shown in Fig. 4 thereby permitting the split sole to be withdrawn from the machine without the danger of splitting the flap. Since the construction and operation of this mechanism is described in detail in the above-mentioned United States Letters Patent No. 1,638,929, it will not be necessary further to describe the same herein.

Having described the invention, what we claim as new and desire to secure by Letters Patent of the United States is:

1. In a splitting machine, a fixed knife provided with an elongated cutting edge, a feed member, means for initially adjusting said feed member with relation to the cutting edge of the knife to provide a gap of predetermined width in accordance with the desired thickness of a piece of material to be trimmed from a work-piece, a yieldable feed member movable with relation to the knife in accordance with the density of the work-piece fed by said members past the knife, and mechanism for causing movement of the yieldable feed member in one direction to effect a proportionately less movement of the other feed member in an opposite direction.

2. In a splitting machine, a fixed knife provided with an elongated cutting edge, a feed member, means for initially adjusting said feed member with relation to the cutting edge of the knife to provide a gap of predetermined width in accord-

ance with the desired thickness of a piece of material to be trimmed from a work-piece, a yieldable feed member movable with relation to the knife in accordance with the density of the work-piece fed by said members past the knife, means for coordinating the movement of the feed members in a predetermined ratio with relation to the knife in opposite directions to cause the width of the gap to be increased or decreased a predetermined amount in accordance with the movement of the second-named feed member, and mechanism for varying said ratio.

3. In a splitting machine, a knife having a cutting edge, a pair of rolls for feeding a work piece against said cutting edge, one of said rolls being adjustable independently of the other with relation to the knife to form initially a gap of a predetermined width between the roll and said cutting edge and the other roll being mounted for yielding movement away from the knife, and connections between the rolls constructed and arranged to cause movement of the yieldable roll in one direction to effect a proportionate movement of said one roll in an opposite direction.

4. In a splitting machine, a knife having an elongated cutting edge, a feed roll, means for initially adjusting said roll with relation to the cutting edge of the knife to provide a gap of a predetermined width, another roll which cooperates with the first-named roll to feed a work piece against said cutting edge, a stop, resilient means for urging the second-named roll toward the cutting edge of the knife until limited by the stop, and mechanism for coordinating movement of the rolls in opposite directions with relation to the knife to vary the width of the gap in accordance with the movement of the second-named roll.

5. In a splitting machine, a fixed knife provided with an elongated cutting edge, a roll initially adjustable with relation to said cutting edge to provide a gap of a predetermined width, a roll movable with relation to the knife in accordance with the thickness and the density of a work piece fed between the rolls, and means for coordinating the movement of the rolls in a fixed ratio in opposite directions with relation to the knife to cause the width of the gap to be increased or decreased a predetermined amount in accordance with the movement of the second-named roll, said means being constructed and arranged for adjustment to vary said ratio.

6. In a splitting machine, a knife having an elongated cutting edge, a feed roll, means for initially adjusting said roll with relation to the cutting edge of the knife to provide a gap of a predetermined width, another roll which cooperates with the first-named roll to feed a work piece against said cutting edge, a stop, resilient means for urging the second-named roll toward the cutting edge of the knife until limited by said stop, mechanism for coordinating movement of the rolls in opposite directions with relation to the knife to vary the width of the gap in accordance with the movement of the second-named roll, and means for limiting the maximum movement of the first-named roll away from the cutting edge of the knife.

7. In a splitting machine, a knife having an elongated cutting edge, a gage roll, means for initially adjusting the gage roll with relation to the cutting edge of the knife to provide a gap of a predetermined width, a roll constructed and arranged to cooperate with the gage roll for feeding a work piece against said cutting edge, means

- for rotating said rolls, a stop, resilient means for urging the second-named roll toward the cutting edge of the knife until limited by said stop, and operative connections between the rolls 5 for causing the same to move proportionate distances in opposite directions with relation to the knife in accordance with variations in the density of the work piece, said connections comprising abutments movable with the second-named roll, 10 a wedge bar which is displaced under the action of said resilient means operating through the work piece and the gage roll, and arms movable against the abutments under the action of said wedge bar until limited by said abutments. 15 8. In a splitting machine, a knife having an elongated cutting edge, a gage roll, means for initially adjusting the gage roll with relation to the cutting edge of the knife to provide a gap

of a predetermined width, a roll which cooperates with the gage roll to feed a work piece against said cutting edge, means for rotating said rolls, a stop, resilient means for urging the second-named roll toward the cutting edge of the knife until limited by said stop, abutments movable toward and away from the knife with the second-named roll, and connections operated by said resilient means through the work piece and the gage roll constructed and arranged to be 10 moved into engagement with the abutments and to permit the gage roll to move under the action of said resilient means operating through the work piece in accordance with the position of the abutments whereby to vary the width of the gap 15 in accordance with the density of the work piece.
